UNITED STATES PATENT OFFICE.

ARTHUR T. CRANE, OF WATERBURY, CONNECTICUT, ASSIGNOR TO THE CHASE COMPANIES INC., OF WATERBURY, CONNECTICUT, A CORPORATION.

VISIBLE-SPARK PLUG.

1,425,748.

Specification of Letters Patent. Patented Aug. 15, 1922.

Application filed June 24, 1920. Serial No. 391,294.

To all whom it may concern:

Be it known that I, ARTHUR T. CRANE, a citizen of the United States, residing at Waterbury, in the county of New Haven and 5 State of Connecticut, have invented a new and useful Improvement in Visible-Spark Plugs; and I do hereby declare the following, when taken in connection with the accompanying drawings and the characters of 10 reference marked thereon, to be a full, clear, and exact description of the same, and which said drawings constitute part of this application, and represent, in—

Fig. 1. A view partly in vertical section 15 and partly in elevation of a visible spark-plug embodying my invention.

Fig. 2. A detached view in side elevation of the terminal-cap.

Fig. 3. A reverse plan view thereof.

20 Fig. 4. A detached perspective view of the sparking-disk.

My invention relates to an improvement in visible spark-plugs, so-called because constructed for the breaking of the current at 25 the upper end of the plug for the production of a visible spark to enable the user to trace the current up to the spark-plug without resorting to any manual tests, the object of my present invention being to produce a 30 simple, convenient and effective plug of the character described, constructed with particular reference to its provision with a definite sparking-point of predetermined location, so that the spark-gap or distance be- 35 tween the sparking-point and the electrode may be accurately pre-gaged, as a manufacturing proposition, whereas in the visible spark-plugs of the prior art, no such point has been furnished and the spark has leapt 40 from the nearest point in the cap to the electrode. A further object of my invention is to provide a sparking-point of a material which will not break down and cause the deterioration of the plug, preferably the same 45 material as the electrode itself.

With these ends in view, my invention consists in a visible spark-plug characterized by a spark-chamber having lateral openings and by a sparking-member carried by 50 the terminal-cap of the plug by which it is spaced apart from the core to assist in forming the spark-chamber and furnishing a sparking-point in line with the electrode of the plug.

55 My invention further consists in certain

details of construction as will be hereinafter described and pointed out in the claims.

In carrying out my invention, as herein shown, I employ a sparking member consisting, as shown, of a disk 2 centrally struck 60 downward to form a sparking-point 3 and having its edges inserted into an annular bead 4 offsetting from the upper corner of a cylindrical terminal-cap 5 set over an integral annular shoulder 6 at the upper end of 65 the insulating-core 7 of the plug which may be of any approved construction and which, as shown comprises a shell 8 in which the core is held by a deformable soft metal gasket 9. 70

The said cap is formed at a point below its bead 4 with an inwardly struck positioning-knurl 10 which rests upon the upper edge of the shoulder 6, whereby the cap is positioned upon the core to which it is 75 firmly secured by spinning its edge inward under the lower edge of the said shoulder to form the retaining-flange 11. The knurl 10 aforesaid is formed with a plurality of round sight-holes or perforations 12 which 80 provide for visualizing, as it were, upon the outside of the cap, the illumination of the interior or spark-chamber 13 thereof, by the 85 sparking taking place when the current leaps from the sparking-point 3 of the disk 2 to the electrode 14 which traverses the center of the core 7 and projects a trifle above the center of the face of the upper end of the core, as shown in Fig. 1. The cap is formed with an externally threaded hollow stem 15 90 for the reception of the usual binding-nut 16.

By preference, the sparking-disk 2 will be made of nickel manganese of the same composition as that used in the electrode 14, though this is not essential. I do not limit 95 myself to the use of nickel manganese either for the electrode or for the disk, but when they are made of the same material, disintegration or the breaking-down of the disk is reduced to the minimum. On the other hand, 100 when brass terminal-caps are used in conjunction with nickel manganese electrodes, as in the visible spark-plugs of the prior art, the brass is gradually broken down and the sparking-gap increased without any 105 means of compensation or control. Under my invention, by the employment of a sparking-disk providing a definite sparking-point, I maintain a fixed sparking-gap, since, as a manufacturing proposition, I am en- 110

abled to predetermine the distance of the disk from the electrode in the assembled device. On the other hand, in the spark-plugs of the prior art, the spark leapt from the nearest point in the cap to the electrode, the point selected by the current being dependent upon the individual variations present in any given plug.

I claim:

- 10 1. A visible spark-plug having a shell, an insulating core, an electrode therein, a terminal-cap positioned upon the core to produce a spark-chamber which is pierced by lateral sight-openings, and a sparking-disk 25 mounted by its edge in the said cap at a point above the said sight-openings and furnishing a sparking-point in line with the said electrode.
- 15 2. A visible spark-plug having a shell, an insulating core, an electrode therein, a terminal-cap positioned upon the core to pro- 30
- 20

duce a spark-chamber which is pierced by lateral sight-openings, and a sparking-disk mounted by its edge in the said cap at a point above the said sight-openings and struck downward to form a sparking-point located in line with the said electrode.

3. A visible spark-plug having a shell, an insulating core, an electrode, a terminal-cap mounted upon the core and formed with an annular bead and with lateral sight-holes located between the bead and the core, and a sparking-disk mounted in the said bead by which it is spaced apart from the core with its center in line with the electrode. 35

In testimony whereof, I have signed this specification in the presence of two subscribing witnesses.

ARTHUR T. CRANE.
